UNITED STATES PATENT OFFICE.

ARTHUR MAILLEFER, OF LAUSANNE, SWITZERLAND.

BLADE PUMP.

Application filed November 12, 1926, Serial No. 148,027, and in Switzerland August 29, 1925.

The subject matter of the present invention is a blade pump.

Figures 1 to 6 in the accompanying drawings illustrate, by way of example, one form 5 of the pump according to the invention in these drawings.

Figure 1 is an end view of the pump, one of the side walls of the fixed cylinder being removed.

Figure 2 is a longitudinal section to a larger scale along the line A—B in Figure 1.

Figure 3 is a diagrammatic end view and shows the relative position of the blade and 15 also that of the ball bearing 21.

Figure 4 is a diagrammatic end view and shows the relative positions of the blade and the inner bearing rings 20 and 18.

Figures 5 and 6 are diagrammatic end 20 views of the cylinder and show the relative positions of the blade and of the inner rings 20 and 18 when the rotatable cylinder makes a quarter of a turn.

The fixed cylinder 1 comprises lateral 25 walls, 2, 2' in which are formed circular apertures serving as lodgements for the ball bearings 3, 3' in the exterior of which rotate the shafts 4, 4' disposed in axial alignment; the shafts 4, 4' each comprise towards their 30 inner end a disc 5, 5' between and in axial alignment with which are mounted by means of the screw-bolts 6, 6' the two shafts forming the rotatable cylinder 7.

The shafts 4, 4' are placed eccentrically 35 relatively to the cavity of the cylinder 1 in such a way that the periphery of the rotatable cylinder 7 penetrates slightly into the fixed cylinder 1, the effect of which is to increase the zone of contact between the 40 rotatable cylinder and make it possible for this region to be made fluid tight.

The eccentric position of the rotatable cylinder 7 in the interior of the cylinder 1 is for the purpose of producing a suction 45 and delivery space indicated by the reference numeral 8.

The two halves of the rotary cylinder 7 are spaced apart in such a way as to leave 50 a central transverse slot 9 between them in the interior of which slot is displaced transversely a blade 10 the ends of which are provided with grooves 11, 11' in each of which are located packing plates 12, 12', placed alternately the ones on the side of the others. The latter are cut out so as to 55 form cavities 13, 13' in the interior of each

of which is located a spring 14 the pressure of which has the effect of pressing the plates 12, 12' against the lateral walls 2, 2' of the cylinder 1.

In addition the plates 12, 12' are constantly pressed against the circular wall of the cylinder 1 by the effect alone of the centrifugal force. In this way the fluid-tight joint is obtained between the ends of 60 the blade and the centre walls of the cylinder 1.

The blade 10 is guided in its movements by means of rollers 15, 15', 15'', against which it presses, the latter being located in 70 cavities formed in the rotatable cylinder 7 and are in addition held in position by means of the screw-bolts 6, 6' around which the said rollers rotate.

The blade 10 is provided on each side at 75 two points equi-distant from its centre with pins 16, 16', 16'', 16''', which pass respectively through radial slots 17, 17', 17'', 17''', formed in discs 5, 5'. The said pins are also attached to the inner bearing rings 18, 18' of the ball bearings 19 and 19' respectively. The outer bearing rings of the latter are secured in circular cavities formed in the bearing rings 20, 20' and placed eccentrically relatively to the bearings 21, 21' in such a way that the ball bearings 19, 19' which are located therein have their centre on a point of the circle 0', Figures 3 to 6.

Thus, on account of the eccentricity of 90 the ball bearings 21, 21' and 19, 19' and when the rotatable cylinder 7 makes a rectilinear to-and-fro movement relatively to the cylinder 7, the effect of which is to make each of the ends of the blade 10 pass out of the 95 periphery of the rotatable cylinder 7, alternately and this takes place while the rotatable cylinder 7 makes one revolution.

Figure 4, 5 and 6 show the ends A—B of the blade 10 in their different positions 100 when the said blade driven by the rotatable cylinder 7 makes a quarter of a turn, while at the same time the eccentric bearing rings 20, 20' make half a turn, that is to say move at a speed which is twice that of the rotatable cylinder 7 and thus give a reciprocating motion to the blade 10.

The eccentric bearing rings 20, 20' each 110 comprise a mass 22, 22' which masses are disposed upon the opposite side relatively to the center 0 of the centre of the blade, these masses being destined to balance the force

of inertia due to the reciprocating motion of the blade 10.

The fixed cylinder 1 is provided with a suction orifice 23 and a delivery orifice 24; 5 the latter may comprise a delivery valve not shown in the drawings.

The operation of the pump is as follows: The shaft having been put into rotation by any source of power, for example by means 10 of a pulley or by direct engagement upon the driving shaft by means of a muff coupling, rotates the cylinder 7 and also the blade 10. The latter is coupled by means of the pins 16, 16', 16'', 16''' to the eccentric 15 ball bearings 19, 19'. The latter drive the bearings 21, 21', the outer bearing rings of which are supported upon the lateral walls 2, 2' of the fixed cylinder 1.

As the speed of rotation of the bearing 20 rings 20, 20' is twice the speed of the rotatable cylinder 7, it follows that while the latter makes one turn the blade 10 is given rectilinear to-and-fro movement in such a way that in turn each of the said blades 25 passes out of the periphery of the rotatable cylinder 7.

Thus, each time end of the blade 10 passes in front of the suction orifices 23 the fluid contained in the compression space 8 is delivered, from which space the said fluid 30 escapes through the delivery orifice 24, which is provided with a delivery valve not shown in the drawings, and from which the fluid is led to the place where it is to be employed.

Having now particularly described and ascertained the nature of my said invention and in what manner the same is to be performed, I declare that what I claim is:—

1. A blade pump, characterized by the 40 feature that it comprises a fixed cylinder provided with suction and delivery orifices in the interior of which moves a rotatable cylinder, the shaft of which is placed eccentrically in such a way that the periphery 45 of the rotatable cylinder penetrates slightly into the fixed cylinder with which it thus presents a large contact zone a suction and delivery space, the rotatable cylinder comprising a central transverse slot, in which 50 moves transversely a blade, the ends of which are provided with packing plates

which come into contact with the inner walls of the fixed cylinder, the blade being given rectilinear to-and-fro movement relatively to the rotatable cylinder by means of a ball bearing eccentric relatively to the shaft of the rotatable cylinder in the lateral wall of the fixed cylinder, the inner bearing ring of which ball bearing also comprises a circular cavity placed eccentrically relatively 60 to the first ball bearing, in the interior of which cavity is located a second ball bearing the inner bearing ring of which is connected to the blade by pins, the whole arrangement being so constructed that when 65 the rotatable cylinder makes one turn the blade is driven alternately in one direction and the other in such a way that its issuing end is constantly in contact with the inner wall of the fixed cylinder. 70

2. A blade pump according to claim 1, characterized by the feature that the inner ring of the eccentric ball bearing pressing upon the fixed cylinder is provided with a mass placed opposite relatively to the centre 75 of this bearing, the centre of the blade, the said mass being destined to balance the inertia force due to the to-and-fro movement of the blade.

3. A pump of the character described 80 comprising a casing, a pair of shafts eccentrically journaled within said casing, a disc carried by each shaft, a rotatably cylinder arranged within said casing, a blade slidably mounted within said cylinder, packing plates 85 extending from the opposite ends of said blade and adapted to contact the inner walls of said casing, oppositely positioned rollers journaled within said cylinder and adapted to ride upon the opposite sides of said blade, 90 laterally extending pins carried by said blade and projecting through radial slots formed within said discs, ball bearing rings connected to said casing and arranged concentrically about said shafts, a weighted 95 means eccentrically rotatable about said ball bearing rings and connected to said pins. 95

Dated this 21 September, 1926.

In witness whereof I have hereunto set my hand.

ARTHUR MAILLEFER.
